COFFEE MAKER

Abraham S. Levin, Philadelphia, Pa.

Application December 12, 1947, Serial No. 143,108

Term of patent 7 years

(Cl. D44—26)

To all whom it may concern:

Be it known that I, Abraham S. Levin, a citizen of the United States of America, residing in Philadelphia, Pennsylvania, have invented a new, original, and ornamental Design for a Coffee Maker, of which the following is a specification, reference being had to the accompanying drawing, forming part thereof, and in which:

Fig. 1 is a perspective view of a coffee maker, showing my new design.

Fig. 2 is a top plan view of the same.

I claim:

The ornamental design for a coffee maker, as shown.

ABRAHAM S. LEVIN.
